UNITED STATES PATENT OFFICE.

DORSEY F. ASBURY, OF WASHINGTON, DISTRICT OF COLUMBIA.

VALVE-OPERATING MECHANISM.

Application filed February 21, 1924. Serial No. 694,368.

My invention relates to valve operating mechanisms of the rocker arm type, and my purpose is to improve the construction and mode of operation of such mechanisms whereby noise, wear and the necessity for lubrication and frequent adjustments of parts is eliminated, all as set forth in my prior applications 374,996 and 374,998, of which this application, in part, is a continuation. Said applications have matured into patents numbered 1,557,548, of Oct. 20, 1925, and 1,493,420, of May 6, 1924, respectively.

My inventive idea is capable of embodiment in different mechanical structures, certain of which are shown in the accompanying drawings, but it is to be understood that the structures shown are merely intended as disclosures of the essential features and novel characteristics of my invention in certain preferred forms and that its scope is as defined in the appended claims.

In the drawings, wherein like characters of reference denote corresponding parts in the different views—

25 Figure 1 is a vertical section of a valve operating mechanism embodying the novel features of my invention, the parts being shown in the positions they occupy when the valve is closed;

30 Figure 2, a view similar to Figure 1 showing the positions of the parts when the valve is open;

Figure 3, a transverse section on the line 3—3 of Figure 1;

35 Figure 4, a perspective of the rocker arm fulcrum member;

Fig. 5 is a perspective view of the rocker arm.

40 Figure 6, a view similar to Figure 1 of a modified form of my improved mechanism; and

Figure 7, a transverse section on the line 7—7 of Figure 6.

Referring to the drawings in detail particularly to Figures 1 to 5 inclusive, 10 designates, generally, an internal combustion engine of the overhead poppet valve type, the same including a cylinder head 11 on the under side of which seats a poppet valve 12, the stem 13 of which extends vertically upward through a guide member 14 in said head and has associated therewith a spring 15 acting to hold the valve normally closed. 15 A push rod 16 constitutes an actuator for said valve and a rocker arm 17 bridges the

upper ends of said push rod and valve stem whereby movement of the former is transmitted to the latter.

At the ends of the rocker arm are recesses 18 and 19 that loosely receive the upper 60 end portions of the push rod and valve stem, respectively, and within said recesses are convex surfaces 20 and 21 respectively, that contact with the flat upper ends of said push rod and valve stem.

At the ends of the rocker arm, intermediate its ends, is a trough 22 which trough is of V-shaped cross section and extends longitudinally of the rocker arm, its end limits being defined by suitable stops or 70 pins 23, 24.

On the engine is affixed a bracket 25 and on a horizontal arm 26 of said bracket is mounted a support for the rocker arm in the form of a flexed leaf spring yoke 27 through 75 which the rocker arm extends and which carries a ball 28 at its upper end seated within the V-shaped trough 22 of the rocker arm, while at its lower end it carries a cylindrical bearing member 29 contacting with 80 the under flat face of said arm 26.

Yoke 27 consists of spaced side portions 30, 31 and upper and lower portions 32, 33, respectively, connecting said side portions, and as a convenient and efficient means of mounting the ball 28 and bearing member 29 on said yoke both the ball and said bearing member are slotted and interfitted with the end connecting portions 32, 33, between and in contact with the side portions 30, 31, 85 90 whereby they are held against movement in all directions with respect to said yoke when the mechanism is assembled.

With the push rod 16 in its lowermost position and valve 12 closed, as shown in Figure 1, the parts of the mechanism are maintained in contact by the inherent resiliency and flexure of yoke 27 which latter is bowed in the direction of the valve stem, but the valve is held against its seat because of the 95 fact that spring 15 is much stronger than the spring constituted by said yoke. When push rod 16 begins to move upward, however, rocker arms 17 fulcrum on the upper end 105 of the valve stem, which latter is held against lateral movement due to its snug fit within guide member 14, until yoke 27 substantially straightens under the operating force thus imparted to the mechanism, ball 28 at the 110 same time rolling on the rocker arm and its

points of contact therewith shifting towards the valve stem due to the yoke being bowed in that direction and when yoke 27 straightens and thus becomes a positive acting element of the mechanism, the fulcrum of the rocker arm is shifted thereto from the valve stem and continued upward movement of the push rod accordingly results in rocking of the rocker arm on the ball 28 with consequent depression of the valve stem and opening of the valve. As the rocker arm rocks on the ball 28, the latter rolls on the rocker arm and its points of contact therewith shift towards the push rod.

15 Since the valve stem 13 cannot move laterally in any direction due to same being guided in member 14, it is necessary, in order to secure rolling contact between its flat upper end and the convex surface 21 of the 20 rocker arm, that the rocker arm be capable of longitudinal movement during operation of the mechanism, and as is apparent, such movement of the rocker arm is permitted because of the fact that it is supported on a 25 swinging fulcrum member. The push rod 16 is flexible and therefore rolls on convex surface 20 of the rocker arm during operation of the mechanism because its flexibility permits it to accommodate itself to movements partaken by the rocker arm. Ball 28 riding in trough 22 provides shiftable rolling contact between the rocker arm and the fulcrum member to accommodate flexures of bowed yoke 27, and cylindrical member 29 provides rolling contact between said fulcrum member and a fixed part of the engine constituted by bracket 25, not only to accommodate flexures of the bowed yoke 27, but to accommodate swinging movements of 40 said yoke.

45 By providing a cylindrical bearing member 29 having line contact with the flat under face of arm 26, the fulcrum member is held against lateral tilting movement transversely of the plane of movement of the rocker arm, and consequently the rocker arm is held against such lateral movement due to the two point contact between ball 28 and the converging surfaces of V-shaped trough 22, while in addition, such two point contact of 50 said ball with said converging or inclined surfaces serves to center the rocker arm with respect to the yoke 27 and thus maintains a working clearance or non-rubbing relation 55 between the sides of the rocker arm and the inner edges of the side portions 30, 31.

60 In the modification of the foregoing arrangement shown in Figures 6 and 7, the fulcrum member 27' which is formed from inherently rigid material, is provided at its upper end with a lateral offset portion 34 overlying the rocker arm and at its lower end with a lateral off-set portion 35 underlying arm 26' of bracket 25'. In the upper face of the rocker arm is formed a V-

shaped trough 22' and in the under face of offset portion 34 is formed a corresponding V-shaped trough 36, while disposed between the rocker arm and said offset portion and having rolling contact with the inclined side walls of both of said troughs is a ball 28'. The troughs 22' and 36 extend longitudinally with respect to the rocker arm and are arcuately curved on radii somewhat longer than the radius of ball 28', so that they form wedge surfaces cooperating with said ball upon longitudinal movement of the rocker arm with respect to the fulcrum member to maintain the parts of the mechanism in contact. A light bowed spring 37 connected at one end to the rocker arm and engaged at its other end with the fulcrum member imparts the necessary force to cause the aforesaid wedging action to maintain the parts of the mechanism in contact.

80 The under face of arm 26' of bracket 25' is convexly curved and the upper face of offset portion 35 of the fulcrum member that contacts therewith is flat whereby rolling contact is provided between the fulcrum member and the bracket and whereby the fulcrum member is held against lateral swinging movement transversely of the plane of movement of the rocker arm, and because of the two-point contact of ball 28' 90 with the inclined surfaces of each trough 22' and 36, the rocker arm is held against like lateral movement as well as out of rubbing contact with the fulcrum member.

95 A pin 38 projects from each fulcrum member and when the latter are arranged in pairs as shown in Figure 7, the ends of the pins engage with each other to hold the fulcrum members against lateral movement transversely of the plane of movement of the 100 rocker arm.

105 In operation, when push rod 16' moves upward the force of spring 37 is overcome and ball 28' first rolls to the lowest point in each trough 22' and 36, the fulcrum member 110 swinging slightly under the influence of the operating force thus imparted to the mechanism to permit such roll, after which the rocker arm rocks on the ball as described in connection with Figures 1 to 5 and the 115 valve is opened.

I claim:—

1. In a valve operating mechanism, a valve including a stem, an actuator, a rocker arm between said valve and actuator, an inherently resilient fulcrum support for said rocker arm movable longitudinally of said rocker arm to permit said rocker arm to roll on said valve stem and acting to maintain the parts of the mechanism in contact, and a connection between said fulcrum support and rocker arm permitting the latter to rock with respect to the former.

120 2. In a valve operating mechanism, a valve including a stem, an actuator, a rocker 125 arm between said valve and actuator, an inherently rigid fulcrum support for said rocker arm movable longitudinally of said rocker arm to permit said rocker arm to roll on said valve stem and acting to maintain the parts of the mechanism in contact, and a connection between said fulcrum support and rocker arm permitting the latter to rock with respect to the former.

130

arm between said valve and actuator, an inherently resilient fulcrum support for said rocker arm movable longitudinally of said rocker arm to permit said rocker arm to roll on said valve stem and acting to maintain the parts of the mechanism in contact, and rolling means between said fulcrum support and said rocker arm.

3. In a valve operating mechanism for engines, a valve including a stem, an actuator, a rocker arm between said valve and actuator, an inherently resilient fulcrum support for said rocker arm movable to permit said rocker arm to roll on said valve stem and acting to maintain the parts of the mechanism in contact, said fulcrum support being supported from a fixed part of the engine, and rolling means between said fulcrum support and said fixed part.

20 4. In a valve operating mechanism, a valve, an actuator, a rocker arm and a fulcrum member therefor the former of which is longitudinally movable with respect to the latter, and rolling means between said fulcrum member and said rocker arm holding the latter against lateral movement with respect to the former.

5. In a valve operating mechanism, a valve, an actuator, a rocker arm and a fulcrum member therefor the former of which is longitudinally movable with respect to the latter and one of which is provided with inclined surfaces, and means between said rocker arm and said fulcrum member rolling on said inclined surfaces and cooperating therewith to hold said rocker arm against lateral movement with respect to said fulcrum member.

40 6. In a valve operating mechanism for engines, a valve, an actuator, a rocker arm between said valve and actuator, a fulcrum member for said rocker arm supported from a fixed part of the engine, rolling means between said fulcrum member and said fixed part, means holding said fulcrum member against lateral movement with respect to the plane of movement of said rocker arm, and rolling means between said fulcrum member and said rocker arm permitting the rocker arm to move longitudinally and holding the same against movement laterally with respect to the fulcrum member.

55 7. In a valve operating mechanism, a rocker arm and a support therefor one of which is provided with a trough of V-shaped cross section extending in a direction longitudinally with respect to the rocker arm, and means rolling in said trough holding the rocker arm against lateral movement with respect to its support.

60 8. In a valve operating mechanism, a rocker arm and a support therefor one of which is provided with a trough extending in a direction longitudinally with respect to the rocker arm, and a single member rolling

in said trough and acting to hold the rocker arm against lateral movement with respect to said support.

9. In a valve mechanism for engines, a rocker arm, a support therefor, and bearing members having slots receiving the ends of said support respectively, one of said bearing members having rolling contact with the rocker arm and the other having rolling contact with a fixed part of the engine. 75

10. In a valve mechanism, a rocker arm, a support therefor, and a bearing member having a slot receiving an end portion of said support and having rolling contact with said rocker arm. 80

11. In a valve mechanism for engines, a rocker arm, a support therefor, and a bearing member having a slot receiving an end portion of said support and having rolling contact with a fixed part of the engine. 85

12. In a valve operating mechanism, a valve including a stem, an actuator, a rocker arm between said valve and actuator, a normally flexed inherently resilient swinging fulcrum member for said rocker arm connected at one end to the engine, and rolling means at the other end of said fulcrum member between said fulcrum member and said rocker arm. 90

13. In a valve operating mechanism, a valve including a stem, an actuator, a rocker arm between said valve and actuator, a resilient fulcrum member for said rocker arm in the form of a leaf spring normally flexed and acting through its resiliency to maintain 100 the parts of the mechanism in contact, said fulcrum member being connected at one end to the engine, and rolling means at the other end of said fulcrum member between said fulcrum member and said rocker arm. 105

14. In a valve operating mechanism, a valve including a stem, an actuator, a rocker arm between said valve and actuator, a support for said rocker arm in the form of a yoke comprising spaced side portions and end portions connecting them, and bearing members at the ends of said yoke having rolling contact, respectively, with said rocker arm and with a fixed part of the engine, said support being inherently resilient 110 and normally flexed whereby it acts to maintain the parts of the mechanism in contact. 115

15. In a valve mechanism for engines, a rocker arm, a support therefor in the form of a yoke comprising spaced side portions and end portions connecting them, and slotted bearing members interfitted by means of their slots with said yoke at the ends thereof and having rolling contact, respectively, with the rocker arm and a fixed part 120 of the engine, said bearing members being disposed between and in contact with said side portions whereby they are held against movement with respect to said support. 125

16. In a valve operating mechanism, a 130

valve including a stem, an actuator, a rocker arm between said valve and actuator, a swinging fulcrum member for said rocker arm, and rolling means between said fulcrum member and said rocker arm, said fulcrum member being inherently resilient and bowed in the direction of said valve stem.

17. In a valve operating mechanism, a valve including a stem, an actuator, a rocker 10 arm between said valve and actuator, a resilient normally flexed fulcrum member for said rocker arm acting through its resiliency to maintain the parts of the mech-

anism in contact and adapted to be straightened under the influence of an operating 15 force imparted to the mechanism, rolling means between said fulcrum member and said rocker arm, and means whereby said rolling means shifts longitudinally of the rocker arm in the direction of said valve 20 stem when said flexed fulcrum member is straightened.

In testimony whereof I hereunto affix my signature:

DORSEY F. ASBURY.
